ATT'YS.

UNITED STATES PATENT OFFICE.

MAGLOIRE METHOT, OF OTTAWA, ONTARIO, CANADA.

SWITCH.

1,217,043.

Specification of Letters Patent. Patented Feb. 20, 1917.

Application filed May 15, 1916. Serial No. 97,733.

To all whom it may concern:

Be it known that I, MAGLOIRE METHOT, a subject of the King of Great Britain, and resident of the city of Ottawa, Province of 5 Ontario, Dominion of Canada, have invented certain new and useful Improvements in Switches, of which the following is the specification.

This invention relates to improvements 10 in switches particularly adapted for use on street railways and the like, and the objects of the invention are to permit of the motor-man actuating the switch without stopping the car, to render the mechanism compact 15 in construction thereby occupying a minimum of space, to obviate jarring on the car during the operation of actuating the switch, to simplify the construction, and generally to adapt the several parts to better 20 perform the functions required of them.

With the above and other objects in view the invention consists essentially of the improved construction particularly described and set forth in the following specification 25 and accompanying drawings forming part of the same.

In the drawings:

Figure 1 is a fragmentary sectional elevation of a street car and railway embodying the present invention.

Fig. 2 is a transverse section through the casing located between the rails.

Fig. 3 is a fragmentary perspective view of the switch and co-acting links controlling the actuation of the same.

Fig. 4 is an end elevation of the wheels co-acting with the casing located between the rails.

Fig. 5 is a transverse section of the casing 40 housing the mechanism located between the rails.

Fig. 6 is a fragmentary perspective view of the bar carrying the wheels for depressing the plungers.

Like characters of reference refer to like 45 parts in the several figures.

Referring to the drawings, A represents a street car of any usual type, and B a railroad provided with switching mechanism C 50 adapted to be controlled from the motor-man's platform D in a manner to be made clear hereafter.

The switching mechanism C comprises a casing 10 provided with a corrugated top 55 11 having angularly disposed ends and de-

signed to house the mechanism controlling the movement of the switch 12.

This mechanism comprises a pair of plungers 13 and 14 pivotally connected at their lower ends to the cranks 15 and 16 60 rigidly mounted on the longitudinally extending and horizontally disposed spindle 17 which extends to a point adjacent to the switch 12, at which end it is provided with a crank member 18, having a slot 19 in the arm thereof in which the bolt 20^a is slidably mounted, this bolt being pivotally connected to one end of the link 20, the other end of the link being connected by a pin 21 to the lower end of the offset link 22, the other end 70 of which is pivotally connected to the switch 12.

The plungers 13 and 14 are provided with enlarged removable heads 23 and 24 which slidably engage with the orifices 25 and 26 75 extending through the top of the casing 10, the lower face of the said heads being adapted to engage with the upper ends of the springs 27 and 28, the lower ends of which engage with the transversely extending members 29 and 30 secured to the sides 80 of the casing.

It will be understood that the cranks 15 and 16 are located diametrically opposite each other so that the spindle 17 is capable 85 of being rotated in both directions effecting the opening and closing of the switch 12.

The spindle 17 is housed in a suitable conduit 31 the rear end of which is connected to the part of the casing 10 which houses the plungers 13 and 14, while the forward end is connected to the casing 31^a 90 which extends transversely between the rails and houses the crank member 18 and links co-acting therewith.

Inspection of the plungers in the casing 10 is conveniently obtained through the door 32 hingedly secured to the top of the said casing and held in elevated or closed position by the fastener 32^a pivotally mounted 100 on the door adjacent to the edge thereof, while to facilitate drawing off surface water liable to collect in the said casing, a drain pipe 33 is provided.

The car apparatus which co-acts with the 105 above described track apparatus consists of a pair of wheels 34 and 35 rotatably mounted on the bifurcated end of the bell crank 36, the arms of which are offset thereby enabling the said wheels to engage with the 110

heads 23 and 24 of the plungers 13 and 14 respectively.

This bell crank is rigidly mounted on the shaft 37 rotatably supported by the bracket 38 from the longitudinally extending bar 39, the reduced ends 39^a of which are slidably embraced by the lower bifurcated ends of the brackets 40 secured to the floor of the car A, the downward motion of said bar 10 being limited by the pins 40^a passing through the said brackets. The upper face of the bar coacts with the springs 41 adapted to obviate any jarring when either of the wheels 34 or 35 coacts with the plunger 15 heads.

It will be readily seen that by reducing the ends of the bar 39, when either of the wheels 34 or 35 engages with the head 23 or 24 of the plungers 13 or 14, any tendency to 20 longitudinal movement of the said bar is eliminated since it will engage with the edges of the brackets 40.

The shaft 37 is provided with a crank arm 42 which is pivotally connected to one end 25 of the link 43, the other end of which is pivotally connected to one arm of the bell crank 44 rotatably supported by the bracket 45 from the bottom of the car A, the other arm 46 of the bell crank being connected 30 to the lower end of the link 47, the upper end of which is connected to the disk 48 carried by the spindle 49 rotatably supported in the quadrant frame 50 secured to the car A adjacent to the control levers so that 35 actuation of the said disk may be readily accomplished by the driver.

To facilitate in rotating the spindle 49 and disk 48 to the desired extent, a lever 51 is provided carrying a suitable detent 52 40 adapted to engage with serrations or teeth 53 provided on the periphery of the casting 50.

The assembly of the switch control will be 45 readily understood from the foregoing description.

When a car fitted with a mechanism of the above description is in use, and when the said car is approaching a switch, the driver actuates the lever 51, which through 50 the medium of the link 47, bell crank 44, link 43, and bell crank 36 and engages the

wheel 34 with the plunger head 23, thereby transmitting motion to the spindle 17 and setting the switch 12 so that the car can travel on its desired course without stopping 55 to effect the positioning of the switch.

Should the driver desire to take the other road, say the side line, the motorman or driver would actuate the lever 51 so that the bell crank 36 would be rotated and permit of the wheel 35 engaging with the plunger head 24, thereby rotating the spindle 17 in the opposite direction to that above described and so open the switch 12 and permit of the car entering the side line. 65

From the above description it will be seen that I have invented a car switch which can be advantageously utilized on street railways, and will permit of switches being operated by the approaching car without 70 the necessity of the said car being brought to a stop.

As many changes could be made in the above construction, and many apparently widely different embodiments of my invention within the scope of the claim, constructed without departing from the spirit or scope thereof, it is intended that all matter contained in the accompanying specification and drawings, be interpreted as illustrative, and not in a limiting sense. 80

What I claim as my invention is:

A device of the class described comprising a casing having a corrugated top provided with angularly disposed ends, plungers slidably mounted in the casing, a longitudinally extending shaft, cranks extending from diametrically opposite sides of the shaft and operatively connected to the lower end of the plungers, a crank on the end of 90 the shaft having a slotted arm, an offset link operatively connected to a rail switch, a link pivotally attached to the offset link and adjustably attached to the said slotted arm, and means for depressing the said 95 plunger.

In witness whereof I have hereunto set my hand in the presence of a witness.

MAGLOIRE METHOT.

Witness:

JAMES MITCHELL.
